(57) **CLAIM**

The ornamental design of a server module enclosure, as shown and described.

DESCRIPTION

FIG. 1 is a left, front isometric view of a server module enclosure, showing our new design;

FIG. 2 is a right, front isometric view thereof;

FIG. 3 is a front view thereof;

FIG. 4 is a left view thereof;

FIG. 5 is a right view thereof; and,

FIG. 6 is a top view thereof.

The appearance of the server module enclosure as seen from the rear and the bottom forms no part of the claimed design.
